UNITED STATES PATENT OFFICE

HEINRICH BERTSCH, OF CHEMNITZ, GERMANY, ASSIGNOR TO H. TH. BOHME AKTIEN-
GESELLSCHAFT, OF CHEMNITZ, GERMANY, A CORPORATION OF GERMANY

FAT CLEAVAGE

No Drawing. Application filed August 26, 1929, Serial No. 388,838, and in Germany October 17, 1928.

The lipolysis or cleavage of fats and oils has been performed hitherto without employing high pressures by heating the same with pure water or water which is only slightly acidulated, the fat or oil to be treated having a cleavage facilitating agent added to it in the form of a product obtained by the sulphonation of a mixture of a fatty acid (or a hardened castor oil) with a hydrocarbon of the benzene series. The use of sulpho-acids of the petroleum hydrocarbons has also been proposed for the same purpose.

As examples of the alcohols which may be employed in the formation of the fat-splitting reagent, there may be named laurin alcohol, olein alcohol, cetyl alcohol and stearin alcohol. These alcohols may be referred to generically and definitely as those alcohols derived from higher fatty acids having more than 8 carbon atoms, by replacement of the carboxyl group by the CH_2OH group.

The object of the present invention is to provide an alternative class of such cleavage facilitating additions. Such are the substances formed by the sulphonation of mixtures of the alcohols corresponding to the higher fatty acids with benzene hydrocarbons. These are excellently suited for the cleavage of fatty acid esters of all kinds, particularly of fats and oils, and are considerably superior in their efficacy to the hitherto known lipolytic agents, especially to the aromatic fatty sulpho-acids. Their greater suitability exhibits itself both in the more rapid progress of the cleavage process and also in the particular purity of the cleavage products obtained which are almost pure white. The differences are due presumably to the better emulsifying powers of the novel cleavage agents towards water-insoluble substances such as fatty acid esters.

The lipolytic media employed according to this invention may be prepared, for example, as follows:

Molecular proportions of olein alcohol and naphthaline are mixed while warming. The mixture is treated with a sulphonating agent such as concentrated sulphuric acid, and is allowed to stand until the reaction is completed. Excess sulphuric acid may be washed out of the reaction mixture with water.

The oily sulphonation product is added to the fatty acid ester to be treated, for instance the fat or oil, the necessary proportion generally not exceeding 1%. The whole is then heated with water whereby smooth cleavage of the ester into fatty acid and

alcohol takes place without any substantial decomposition or discolouration of the cleavage products.

As examples of the members of the benzene series which may be employed, including benzene, naphthalene, and anthracene.

The exact structure of the reagent cannot be definitely given. However, it is believed that the alkyl radical of the alcohol joins directly with the aryl radical of the hydrocarbon thereby eliminating water, and that the simultaneous or subsequent sulphonation introduces a sulphonic group at another point on the aryl radical.

Example

One part by weight of the sulphonation product derived by sulphonating olein alcohol in the presence of naphthalene is added to and stirred carefully into 100 parts by weight of molten tallow. Then 50 parts by weight of water are added and the mass brought to a boil by the introduction of steam. After about 10 hours, the cleavage is substantially complete. The mass is then allowed to settle. Finally, the glycerin and water are drawn off.

I claim:

1. The process of cleaving fatty acid esters comprising heating a fatty acid ester in the presence of water and an agent composed of a sulphonation product derived from the treatment with a sulphonating agent of a mixture of a hydrocarbon of the benzene series and an alcohol corresponding in the number of carbon atoms to a higher fatty acid.

2. In the process of cleaving fatty acid esters by heating in the presence of water, the step comprising treating said fatty acid esters during said heating in the presence of water, with an alkyl derivative of a sulphonated aro-

matic hydrocarbon in which said alkyl radical corresponds to a higher fatty acid in the number of carbon atoms contained therein.

3. The process of cleaving fats and oils comprising adding thereto a sulphonation product produced by sulphonating a mixture of a hydrocarbon of the benzene series with an alcohol derived from a higher fatty acid by replacement of the carboxyl group with 10 a CH_2OH group, and then heating in the presence of water.

4. A process according to claim 3 wherein the proportion of the sulphonation product does not exceed about one per cent.

15 5. In the process of splitting fatty acid esters by heating in the presence of water, the step comprising treating said esters during said heating in the presence of water also with a small quantity of a fat splitting agent 20 derived from the treatment with a sulphonating agent of a mixture of a hydrocarbon of the benzene series with an alcohol derived from a higher fatty acid having more than 8 carbon atoms by replacement of the carboxyl 25 group by the CH_2OH group.
